UNITED STATES PATENT OFFICE.

MATTHEW F. BIERSDORF, OF LOS ANGELES, CALIFORNIA.

MACHINE FOR CUTTING POCKETS IN GARMENTS.

Application filed October 1, 1921. Serial No. 504,751.

To all whom it may concern:

Be it known that I, MATTHEW F. BIERSDORF, a citizen of the United States, residing at Los Angeles, in the county of Los Angeles and State of California, have invented new and useful Improvements in Machines for Cutting Pockets in Garments, of which the following is a specification.

10 This invention relates to a machine for cutting pockets in garments and is particularly adapted for cutting pockets in several pieces of cloth at one time such as is usually done in the manufacture of large quantities 15 of shirts or other such garments.

It is the object of this invention to provide a simple and rapid means by which the several pieces of cloth which are usually stacked one upon the other, can be easily 20 cut.

Another object is to provide a cutter that will partially rotate and will thereby easily cut the cloth without any excess pressure of the cutter upon the goods and the cutter is 25 oscillated so as not to pull the cloth in one direction.

Other objects and advantages will be seen and the invention readily understood from the following description of the accompanying 30 drawings in which:

Fig. 1 is a side elevation of the device, a side plate of the cutter support being removed to show the cutter actuating means.

Fig. 2 is a partial end elevation taken on 35 line 2—2 of Fig. 1.

The device as shown comprises substantially a base 1 having depending legs 2 and 3, the leg 2 having an ordinary U-clamp 4 so as to clamp the device firmly upon a table 40 5 or other suitable object. Projecting upwardly from the leg 3 is a hollow box structure supporting standard 6 within which is mounted a vertical screw threaded shaft 7 suitably journaled at its upper and lower 45 end in bearing supporting members 8 and 9, the lower end of the shaft carrying a bevel gear 10 having engagement with a second gear 11 suitably journaled in the lower portion of the leg 3 and these gears are suitably 50 actuated by the gear train 12, the final gear of which is driven by a shaft 13 suitably journaled in both of the legs and having a crank arm 15 fastened to the outer end so that when the same is rotated, the shaft 7 55 will be rotated also and will cause a supporting arm 16 to be raised and lowered as

by a lug 17 having screw threaded engagement with the shaft 7. The arm 16 which carries the cutting mechanism is slidably supported by the upright 6 by a suitable construction comprising an elongated head 18 having vertical slots 19 formed on each side of the head and adapted to engage the inwardly projecting portions 20 of the front side of the support, a slot being formed between the ends 20. It will thus be seen that the arm 16 will be prevented from having rotatable movement when the screw is rotated.

The support arm 16 which projects forwardly from the head 18 comprises two channel members 21, the backs of which are spaced apart so as to form a guide slot 22. Slidably carried upon the arm 16 is the driving motor 23 mounted upon a base 24 which has a depending guide portion 25 slidably received within the slot 22 and projecting downwardly from this guide portion is the cutter support 26 terminating in a curved portion 27.

When cutting several pieces of cloth, it is necessary that the cutter and support be very thin so that it will easily enter the cloth and to provide this necessary construction the cutter support is shown as two thin plates 27 bolted at their upper ends to a portion 28 depending from the guide portion 25 as by bolts 29 or any other suitable construction. Rotatably mounted upon the lower end of the cutter support is the cutter 30 here shown as suitably journaled in roller bearings 31 mounted upon a shaft 32.

Means for oscillating the cutter by the motor 23 comprises substantially a crank pin 33 formed on one end of the motor shaft and having a connecting rod 34 suitably journaled thereon at one end and connected as at 35 to a guide rod 36 slidably journaled in the forward end of the base of the motor. Connected to the other end of the guide rod is an arm 37 pivotally mounted to the sides 27 as to 38. Connecting links 39 are shown connected at their upper end equi-distance from the pivot point 38 and at their lower end to the cutter 30 and this construction is necessarily very thin so as to make the whole cutter support relatively narrow. One of the plates 27 is shown as cut away at 40 to receive the arm 37, at 41 to receive the arms 39 and at 42 to receive the cutter and the other plate will fit against the projecting

portions formed by the portions cut away. By such a means a very rigid construction is obtained. It will thus be seen that if the motor is operated the cutter 30 will 5 oscillate so as to easily cut the cloth.

To hold the cloth while it is being cut, a clamp member 43 is shown as vertically slidably mounted upon clamping supports 44 and the clamping member can have any 10 suitable clamping means such as an eccentric actuated by a lever arm 45 and adapted to engage the supports 44. A longitudinal slot 46 is formed in the base so as to allow the cutter to pass through the same.

15 Suitable adjusting means are provided so as to allow the cutter to be moved forwardly and backwardly so that the cloth can be cut at any desired position within range of the device. Such a construction embodies a 20 rack 47 mounted upon the upper side of the lower flange of one of the channel members 21 and depending from the base of the motor on the outside of the channel members are bearing supports 48 suitably cross connected beneath the channel members. 25 Journaled in one of the supports 48 is a shaft 49 carrying a pinion 50 adapted to engage the rack 47 and having any suitable actuating means such as a knob fastened on the shaft 49 and it will thus be seen that as the pinion is rotated, the cutter and 30 motor will be shifted longitudinally and to clamp the same in any desired position, suitable clamping means such as an eccentric 35 51 is carried by a shaft journaled in the opposite supporting arm 48 and has an actuating lever 52. The clamping means for the member 43 is similar to that just described.

40 In the operation it will thus be seen that the general construction will allow the cutter to be shifted longitudinally and also vertically which latter adjustment actuated by the crank arm 15, allows the cutter to cut 45 down through the cloth.

Various changes may be made in the details of construction by those skilled in the art, without departing from the spirit of my invention as set forth in the 50 appended claims.

What is claimed is:

1. In a machine for cutting pockets or the like in garments comprising a base to support said garments or the material for 55 the same, a cutter, and means for independently moving said cutter vertically toward and away from the base and horizontally across the base.

60 2. In a machine for cutting pockets or the like in garments comprising a base to support said garments or the material for the same, an oscillatory cutter, means for actuating said cutter, means for vertically moving said cutter relative to said garments, and means for allowing said actuating

mechanism to be passed through the opening cut in said garment without having contact with the same.

3. In a machine for cutting pockets or the like in garments comprising a base to support said garments or the material for the same, a vertical support, a horizontal arm slidably supported by said vertical support, means for vertically shifting said arm upon said support, a member slidably supported by said arm, means for horizontally shifting said member upon said arm, cutter supports depending from said member, a movable cutter journaled between and in said supports, cutter actuating mechanism suitably mounted between and on said supports, a motor carried by said member, and means for actuating said cutter mechanism by said motor.

4. In a machine for cutting pockets or the like in garments comprising a base to support said garments or the material for the same, a vertical support, a horizontal arm supported by said vertical support, a member supported by said arm, cutter supports depending from said member, a cutter journaled in said supports, cutter actuating mechanism suitably mounted on said supports, and means for actuating said cutter mechanism to effect oscillatory movement of 95 said cutters.

5. A cloth cutting machine comprising a support mounted for vertical and horizontal adjustments, a cutter journaled on the support, a motor sustained on the support, and means operable by said motor for effecting oscillation of the cutter comprising an arm fulcrumed on the support, links connected to the arm and to said cutter at opposite sides of its axis, and a crank operatively connected to the shaft of said motor and to said arm for effecting a rocking movement of the latter.

6. A cloth cutting machine comprising a support, a cutter journaled on the support, a motor sustained on the support, and means operable by said motor for effecting oscillation of the cutter comprising an arm fulcrumed on the support, links connected to the arm and to said cutter at opposite sides of its axis, and a crank operatively connected to the shaft of said motor and to said arm for effecting a rocking movement of the latter.

7. A cloth cutting machine comprising a support, a screw threaded shaft journaled in the support, a head slidable vertically on the support, a sleeve connected to the head and threadedly engaging said shaft, an arm fixed to said head, a base slidable on the arm, a rack formed on the arm, a pinion journaled on the base and engaging the rack for effecting a horizontal adjustment of the base, a motor supported on the base, a cutter journaled in the base, mechanism oper-

able by said motor for effecting an oscillatory movement of said cutter, means for locking the base in adjusted position upon the arm, and means for actuating said shaft 5 whereby said sleeve is operated to effect a vertical adjustment of said head and arm.

8. A cloth cutting machine comprising a support having an opening formed therein, means adjacent the opening for clamping 10 the material to be cut in overlying position with respect to the opening, an arm mounted for vertical adjustment on the support, a base slidable on the arm, means for adjusting the base horizontally on the arm and 15 securing said base in any adjusted position, a motor sustained on the base, a cutter journaled on the base and adapted through the

vertical adjustment of said arm to be moved vertically through said opening, and means operable by said motor for oscillating the 20 cutter irrespective of its vertical or horizontal adjustment.

9. A cloth cutting machine comprising a knife mounted for oscillatory movement and having a curved cutting edge, means for 25 oscillating the knife, means for sustaining the operating means and knife for movement into a plurality of layers of cloth, and means for housing the operating means to prevent its contact with the cloth. 30

In testimony whereof I have signed my name to this specification.

M. F. BIERSDORF.
